(57) CLAIM

The ornamental design for a guitar shaped drinking vessel, substantially as shown and described.

DESCRIPTION

FIG. 1 is a front perspective view of a guitar shaped drinking vessel comprising a first embodiment of a new, original and ornamental design;

FIG. 2 is a front view of the guitar shaped drinking vessel of FIG. 1 comprising the new, original and ornamental design;
FIG. 3 is a left side view of the guitar shaped drinking vessel of FIG. 1 comprising the new, original and ornamental design;

FIG. 4 is a rear view of the guitar shaped drinking vessel of FIG. 1 comprising the new, original and ornamental design;
FIG. 5 is a right side view of the guitar shaped drinking vessel of FIG. 1 comprising the new, original and ornamental design;

FIG. 6 is a top view of the guitar shaped drinking vessel of FIG. 1 comprising the new, original and ornamental design;
FIG. 7 is a bottom view of the guitar shaped drinking vessel of FIG. 1 comprising the new, original and ornamental design;
FIG. 8 is a front perspective view of a guitar shaped drinking vessel comprising an additional embodiment of a new, original and ornamental design;

FIG. 9 is a front view of the guitar shaped drinking vessel of FIG. 8 comprising the new, original and ornamental design;
FIG. 10 is a left side view of the guitar shaped drinking vessel of FIG. 8 comprising the new, original and ornamental design;

FIG. 11 is a rear view of the guitar shaped drinking vessel of FIG. 8 comprising the new, original and ornamental design;
FIG. 12 is a right side view of the guitar shaped drinking vessel of FIG. 8 comprising the new, original and ornamental design;

FIG. 13 is a top view of the guitar shaped drinking vessel of FIG. 8 comprising the new, original and ornamental design; and,

FIG. 14 is a bottom view of the guitar shaped drinking vessel of FIG. 8 comprising the new, original and ornamental design.

The broken line portion of the figure drawings is included to show unclaimed subject matter only and forms no part of the claimed design.
